CLAIM

The ornamental design for a GPS exercise monitoring device, as shown and described, those portions shown in broken lines being for illustrative purposes only and forming no part of the claimed design.

DESCRIPTION

FIG. 1 is a first perspective view of a GPS exercise monitoring device according to the present invention;

FIG. 2 is a second perspective view thereof;

FIG. 3 is a top plan view thereof;

FIG. 4 is a bottom plan view thereof;

FIG. 5 is a first end view thereof;

FIG. 6 is a second end view opposite the first end thereof;

FIG. 7 is a left side view thereof; and,

FIG. 8 is a right side view thereof.

Those portions shown in broken lines are for illustrative purposes only and form no part of the claimed design.
